Attorney

UNITED STATES PATENT OFFICE.

SIMEON P. MISTRAL, OF GALVESTON, TEXAS.

CLOTHES HOOK.

Application filed May 19, 1922. Serial No. 562,111.

To all whom it may concern:

Be it known that I, SIMEON P. MISTRAL, a citizen of the United States, residing at Galveston, in the county of Galveston and 5 State of Texas, have invented a new and useful Clothes Hook, of which the following is a specification.

This invention relates to a clothes hook, one of its objects being to provide a simple 10 and inexpensive device of this character which can be formed of wire or other material and is so shaped as to provide efficient means for holding a coat or skirt in the same manner as is possible with an ordinary 15 coat hanger, there being additional means for supporting a hat or other garment.

Another object is to provide devices of 20 this character which can be used in lieu of the old forms of clothes or garment hooks simply by screwing them into supporting structures.

With the foregoing and other objects in view which will appear as the description 25 proceeds, the invention resides in the combination and arrangement of parts and in the details of construction hereinafter described and claimed, it being understood that, within the scope of what is claimed, changes in the precise embodiment of the 30 invention shown can be made without departing from the spirit of the invention.

In the accompanying drawing which is a perspective view of the device, the preferred 35 form of the invention has been shown.

Referring to the drawing by characters 40 of reference 1 designates a stem formed by threading one end portion of a stiff wire, this wire being looped to provide straight parallel arms 2 and 3 the merging portions 45 of which are upturned as at 4 to form the terminal of a hook designed to support a hat or other garment. That end of the arm 3 nearest the threaded portion 1 is bent downwardly over the arm 2 to provide a depending arm 5 the lower portion of which is 50 curved forwardly as at 6 and upwardly as at 7 where it merges into the lower portion of a laterally extended loop 8. The end portions or terminals of the loop are preferably downturned as shown at 9 in Figure 2 so that a coat hanger is thus provided. A

member 10 is extended from the bottom portion of the loop 8 and extends parallel with the parts 7, 6 and 5, this portion 10 terminating in a coil 11 which is formed 55 around that portion of the arm 2 nearest the threaded end 1.

It will be apparent that by shaping the wire as described and shown the article produced can be connected readily to a supporting structure simply by screwing the end 1 into the structure until the depending arm 5 comes against the structure so as to be braced thereby. Thus a garment can be placed on the upturned portion 4 while a coat, skirt or the like can be placed on the hanger 8. It will be noted that arm 5 loops or crosses over arm 2 and where arm 5 merges into arm 3 it is engaged by the coiled end 11 of arm 10. Thus any load to 70 which arms 5 and 10 may be subjected will be supported by the arm 2. Consequently 65 both arms 5 and 10 serve to support garments placed on loop 8. The coil 11 is carried solely by the arm 3 and constitutes a 75 means for holding the arms 2 and 3 properly spaced apart where the arms 5 and 10 are located. Thus the rigidity of the loop formed by the arms 2 and 3 is increased.

While the device has been shown and described as made of stiff wire it is to be understood that it can be formed of any other suitable material. Furthermore the hat hook can be dispensed with if so desired.

What is claimed is:—

A clothes hook formed in a single length of wire bent to form an elongated loop having straight parallel arms, a support engaging screw formed by one end of one of the arms, a depending portion extending 90 over and downwardly from the screw-carrying arm and merging into a forwardly extending portion upturned at one end and merging into the lower portion of a laterally extended loop, and a member integral 95 with and extending from the bottom portion of said loop and parallel with the depending arm and its forward extension, said member having a terminal coil engaging that arm of the elongated loop from 100 which the depending arm extends, the screw-carrying arm being extended between

the depending arm and that portion parallel therewith and constituting a support for a load carried by both the depending arm and the member parallel therewith, the said 5 coil constituting means for spacing the side portions of the elongated loop.

In testimony that I claim the foregoing

as my own, I have hereto affixed my signature in the presence of two witnesses.

SIMEON P. MISTROT.
